UNITED STATES PATENT OFFICE.

JOHN W. FREDRICK, OF INDIANAPOLIS, INDIANA.

PRESS FOR BRAN, COTTON-SEED, &c.

SPECIFICATION forming part of Letters Patent No. 247,898, dated October 4, 1881.

Application filed July 6, 1881. (No model.)

To all whom it may concern:

Be it known that I, JOHN W. FREDRICK, of Indianapolis, in the county of Marion and State of Indiana, have invented certain useful 5 Improvements in Presses for Bran, Cotton-Seed, &c., of which the following is a specification.

My improvement relates to the operation of hydraulic presses in the compression of various materials into cakes, and has for its object 10 to accomplish the quick removal without breakage of the compressed cake. For that purpose I utilize the same power used for the compression to force the cake out of the truss or 15 box, as hereinafter described and claimed.

In the accompanying drawings, Figure 1 is a sectional elevation of a press as arranged for removal of the cake. Fig. 2 is a horizontal section on line *x x* of Fig. 1; and Fig. 3 is a 20 perspective of one blocking-piece used for sustaining the press-box.

Similar letters of reference indicate corresponding parts.

The press shown is an ordinary hydraulic 25 press.

A is the cylinder; *B*, the ram or follower, working in the cylinder.

C are posts or standards, supporting top 30 plate, *F*, and the fixed cylinder or platen *E*.

D is the truss or box; and *I* is a cap placed on ram or follower *B*, for supporting the box.

K is a windlass or shaft, sustained in bearings on two of the posts *C*, from which chains or ropes *a a* pass upward over pulleys *b* at the 35 top of the press. These ropes carry hooks at their ends for connection to the box *D*, so that by operation of the shaft by means of its crank-handle to wind the rope the box is raised on the fixed cylinder *E*.

L are blocks, one of which is shown in

Fig. 3, inserted below box *D*, for sustaining the same a suitable distance above the cap *I*.

The press is to be operated for compression of the material in the usual manner—that is to say, the box *D* is drawn out upon a bench 45 filled with material, and then moved back upon the cap *I*. Pressure is then applied to ram *B* by forcing liquid into cylinder *A*, and box *D* being thereby raised on the fixed cylinder *E*, the material is pressed.

To remove the compressed cake, I raise the box *D* by operation of the shaft *K*, place the blocks *L* on the cap *I*, and lower the box upon the blocks to the position, as shown in Fig. 1. Pressure is then applied to raise the ram *B*, 55 blocks *L*, and box *D*, and the compressed cake is forced down and out at the lower end of box *D*. By these means the cake is quickly removed, and is preserved whole, which is of 60 any useful material.

The invention is applicable in the work of pressing sawdust for fuel, compressing meal, bran, cotton-seed, and other material.

Having thus fully described my invention, I 65 claim as new and desire to secure by Letters Patent—

In a press, the combination, with the moving ram *B*, the fixed cylinder *E*, and the press-box *D*, adapted to be raised upon the said cylinder, of the removable blocks *L*, provided with side projections, and adapted to be placed between the said box and ram, whereby the cake will be forced out of the press-box when the ram is elevated, substantially as set forth. 75

JOHN WILLIAM FREDRICK.
